UNITED STATES PATENT OFFICE.

AUGUST G. DAHMER, OF ALAMEDA, ASSIGNOR OF ONE-THIRD TO FREDRICK EICHENHOFER, OF LOS ANGELES, CALIFORNIA.

ROOF-FRAMING RULE.

SPECIFICATION forming part of Letters Patent No. 499,521, dated June 13, 1893.

Application filed February 12, 1892. Serial No. 421,264. (No model.)

To all whom it may concern:

Be it known that I, AUGUST G. DAHMER, of Alameda, in the county of Alameda and State of California, have invented a new and useful Improvement in Roof-Framing Rules, of which the following is a full, clear, and exact description.

My invention relates to a rule especially adapted for use in framing the roofs of buildings, and has for its object to so construct the rule that the pitch and run of the rafter being known, the altitude and the length of the rafters may be expeditiously, conveniently and accurately read; and the invention consists in the novel construction of the rule and in the combination of its parts, as will be hereinafter more fully set forth and pointed out in the claim.

Reference is to be had to the accompanying drawings forming a part of this specification, in which similar figures and letters of reference indicate corresponding parts in all the views.

Figure 1 is a plan view of the reverse side 25 of the rule. Fig. 2 is a similar view, partially in perspective, of the obverse side. Fig. 3 is a partial perspective view of one end of the rule, illustrating the obverse side of said end, the slide being moved to show the scale at the 30 extremity; and Fig. 4 is a perspective view of a portion of the rule, showing the end scale upon the obverse side, and the slide as carried from the rule.

The body of the rule A, may be made of any 35 approved material, such as wood or metal, and may be of any desired dimensions. One end of the rule is thicker than the remaining portion, whereby projected faces 10 and 11, are formed at each side. At the opposite end of 40 the rule a slide 12, is loosely mounted upon the body, capable of being removed therefrom if desired, and of being carried over the faces of said body to the projected faces 10 and 11 when necessary. The slide 12, may be of any 45 suitable or approved construction, and consists ordinarily of a block having an opening from side to side to receive the body of the rule, and outwardly projected arms 13, at top and bottom to guide it truly over the faces of 50 the body and prevent it from assuming a diagonal position.

Each side of the rule is provided with scales longitudinally produced thereon, one beneath the other, the scales being graded or graduated in accordance with certain pitches of the 55 roof. The scales are produced in feet and inches, and the series at each side may consist of any desired number of scales.

In the rule shown in the drawings there are seven scales upon each side, the first scale being designated as 14^a, the second as 14^b, the third as 14^c, the fourth as 14^d, the fifth 14^e, the sixth 14^f and the seventh 14^g. Upon the projected face 10 on the reverse side of the rule seven spaces are produced, a space forming 65 practically a continuation of each of the scales. In the first space the fraction "½" and the words "Height rafter" are produced and in the second "½ hip rafter;" the third space contains "½ common rafter," and in the 70 fourth space the word "Run" is produced; in the fifth space "½ common rafter" is printed or produced, and in the two remaining spaces "½ hip rafter" is produced upon the upper, and "½ height rafter" upon the lower, the fractions referring to the pitch of the roof.

The spaces upon the projected face 11 at the obverse side of the body contain the following matter in the order enumerated: "½ 80 height rafter;" "½ hip rafter;" "½ common rafter;" "Run;" "½ common rafter;" "½ hip rafter;" "½ height rafter." Upon the reverse side of the slide spacings are produced corresponding to those upon the reverse projected face 10 and containing the following matter 85 in the order specified: "½ pitch height of rafter;" "½ pitch hip rafter;" "½ pitch common diagonal rafter;" "Run of rafter;" "½ pitch common rafter;" "½ pitch hip rafter;" "½ pitch height of rafter." Upon the obverse 90 side of this slide this matter is arranged in the following order: "½ pitch height of rafter;" "½ pitch hip rafter;" "½ pitch common rafter;" "Run of rafter;" "½ pitch common rafter;" "½ pitch hip rafter;" "½ pitch height 95 of rafter."

Upon the reverse side of the square or rule, at the end over which the slide is entered, opposite the upper scale 14^a the following matter is produced: "Octagon face;" opposite the 100 second scale 14^b this matter is produced,— "1 1/7 P. L. (plumb level), 1 1/7 T (top cut);"

posite the third scale 14° this matter appears: "1 $\frac{1}{2}$ P. L., 1 $\frac{8}{10}$ 5;" opposite the fourth scale 14° the phrase "Octagon center," is produced; opposite the fifth scale 14° the following matter is printed: "1 $\frac{9}{12}$ P. L., 1 $\frac{8}{10}$ I. J." and opposite the sixth scale 14° this matter is arranged, namely,—"1 $\frac{9}{12}$ P. L., 1 $\frac{4}{10}$ 2." At this end of the body of the rule, upon the obverse side opposite the second scale thereon 14°, the following matter is printed: "1 $\frac{12}{12}$ P. L., 1 $\frac{9}{11}$ T;" opposite the third scale 14° this matter appears: "1 $\frac{12}{12}$ P. L., 1 $\frac{2}{12}$ diagonal;" opposite the fifth scale 14° this matter is produced: "1 $\frac{8}{12}$ P. L., 1 $\frac{9}{12}$ T. J.;" opposite the sixth scale 14° the matter "1 $\frac{9}{12}$ P. L., 1 $\frac{9}{12}$ 10 T" is arranged. Now the run of the rafters and the pitch having been determined upon, the length of the rafters may be obtained expeditiously, conveniently and accurately, as heretofore stated by moving the slide 12 over the body of the rule. Supposing the run of the rafter is eight feet and the pitch one-third; the slide is moved over the body of the square or rule until the inner edge or margin of the slide at the space containing the words "Run of rafter" registers with the figure 8 which is the run required. The height or elevation of the rafter will be read on the lower scale opposite "1 $\frac{1}{3}$ pitch height of rafter" upon the slide. It will be observed that the reading of this scale will be five feet, four inches, and the length of the common rafter will be nine feet, eight inches, and the length of the hip rafter twelve feet, six inches.

Other pitches of roofs than those illustrated 35 may be used upon or added to this rule, upon

the same principle as herein set forth, and the rule may be extended to any length, with corresponding lengths of rafters to the number of spaces in feet and inches, and the slide 12 can be left at any point on the rule and the 40 corresponding lengths and heights of both common and hip rafters can be read on the rule at the bevel edge of the slide.

Having thus described my invention, I claim as new and desire to secure by Letters 45 Patent—

A roof framing rule A having a central longitudinal line of graduations indicating the run of a rafter in feet, and fractions thereof, series of parallel graduations at opposite sides 50 of said first graduation and each indicating different pitches, heights, and lengths of either hip or common rafters or fractions thereof, without calculation, the said series of graduations being relatively arranged with respect 55 to the central line of graduations but independent of each other, to give the entire lengths and cuts of the entire set of said rafters, and a slide mounted on the rule to align any one of the graduations of the run of the 60 rafter with one or more of the desired graduations on opposite sides thereof, and said slide bearing indications similar to said indication at the beginning or end of the rule substantially as described and in the manner 65 and for the purpose set forth.

AUGUST G. DAHMER.
